[57] CLAIM

The ornamental design for an element of a shoe upper, as shown and described.

DESCRIPTION

FIG. 1 is a top plan view of a shoe upper having an element showing my new design;

FIG. 2 is a left side elevational view thereof;

FIG. 3 is a right side elevational view thereof; and,

FIG. 4 is a rear elevational view thereof.

The broken line showing of the remainder of the shoe, including the lacing elements, is for illustrative purposes and forms no part of the claimed design.
